UNITED STATES PATENT OFFICE.

LYMAN H. ZEIGLER, OF REDKEY, INDIANA, ASSIGNOR TO HIMSELF AND
JACOB A. HORN, OF SAME PLACE.

FIRE-ENGINE.

SPECIFICATION forming part of Letters Patent No. 268,295, dated November 28, 1882.

Application filed March 7, 1882. (No model.)

To all whom it may concern:

Be it known that I, LYMAN H. ZEIGLER, of Redkey, in the county of Jay and State of Indiana, have invented a new and Improved 5 Fire-Engine, of which the following is a full, clear, and exact description.

The invention consists in a pump pivoted in a frame mounted on a U-shaped axle supported on wheels, which frame is provided 10 with a draft-pole, whereby the axle can be swung upward, so that the pump and frame will be raised during transportation; or the axle can be swung downward, so that the frame rests on the ground and forms a firm bearing 15 for the pump during operation. The frame is provided with a tongue or pole for pulling or pushing the engine, and with pivoted braces for locking the parts in position when the axle is raised.

20 Reference is to be had to the accompanying drawings, forming part of this specification, in which similar letters of reference indicate corresponding parts in all the figures.

Figure 1 is a longitudinal elevation of my 25 improved fire-engine, showing it raised for transportation, parts being broken out. Fig. 2 is a longitudinal elevation of the pump-cylinder of the same. Fig. 3 is a cross-sectional elevation of my improved fire-engine on the 30 line x x, Fig. 1, showing it lowered for operation.

The ends of a U-shaped axle, A, are journaled in the hubs of two wheels, B, of the usual construction. The cross-piece of the U-shaped 35 axle A is also journaled in the base of a frame, C, to which frame a draft-pole or tongue, D, is attached, which is at right angles to the axle, and is provided at the ends with handles a or other equivalent devices for holding the pole 40 or tongue D to pull or push the wheels and frame C. A brace-bar, E, is pivoted on the axle next to the frame C, and is provided at its free end with a hook, F, fitting in a staple or loop, G, on the pole or tongue D; or the 45 brace-bar can be provided with other devices for locking it to the pole or tongue D. A brace, H, is pivoted on the axle A adjoining one of the wheel-hubs, and to the brace-bar E near the end of the same. A cylinder, J, is pivoted 50 in the frame C to adapt it to be oscillated, and this cylinder is provided at the bottom with a

valve-box, K, divided into two compartments, K', by a partition, b, each compartment containing a valve, L. This valve-box K is connected with the suction-pipe M. A valve-box, 55 N, provided with an air-chamber, O, is located on the top of the cylinder J, and contains two valves, P. This valve-chamber N is connected with the delivery-pipe Q. The cylinder J, which may be open or closed at the 60 ends, is divided into two compartments by a central transverse partition, R, containing a packing, R', for the piston-rod S, passing longitudinally through the cylinder. A piston, T, is rigidly mounted on the rod S at each side of 65 the transverse partition R. One end of the piston-rod S is pivoted to a beam, V, pivoted on the top of the frame in the direction of the length of the tongue D, which beam is provided at the ends with handles W and trans- 70 verse rods Y, or equivalents.

The operation is as follows: During transportation of the engine the axle A is raised, so that the bottom of the frame C will be as high as the upper parts of the wheels, the axle 75 being locked in this position by means of the brace E. The tongue or pole D can then be used to pull or push the engine. If the engine is to be used, the end of the brace E is detached from the pole or tongue D, and the axle A is 80 swung one hundred and eighty degrees—that is, it is swung downward, so that the pole D rests on the ground and forms a good bearing for the engine, and holds the same in place during operation. The length of the shanks 85 of the U-shaped axle A is such that when the axle is swung downward the pole or tongue D will rest on the ground. By working the beam V up and down the piston-rod S will be reciprocated, and the pump will operate in the same 90 manner as the usual double-acting pumps. The working of the beam V causes an oscillation of the cylinder, and for that purpose I pivot the cylinder in the frame C.

The herein-described fire-engine is very simple in construction, is very light, can be transported very easily, and stands firmly during operation.

Having thus fully described my invention, what I claim as new, and desire to secure by 100 Letters Patent, is—

1. The combination, with a pump and its

frame, of a U-shaped axle for supporting the frame, and wheels for supporting the axle, substantially as herein shown and described, whereby the frame and pump can be raised 5 during transportation, and can be lowered to rest on the ground during operation, as set forth.

2. The combination, with a pump, of the pump-frame C, the pole or tongue D, the U-shaped axle A, the wheels B, and the brace E H, substantially as herein shown and described, and for the purpose set forth.

3. The combination, with a pump, of the pump-frame C, the pole or tongue D, the U-shaped axle A, the wheels B, the brace E H,

and the pivoted beam V for operating the pump, substantially as herein shown and described, and for the purpose set forth.

4. In a fire-engine, the combination, with the supporting-frame C, of the cylinder J, pivoted 20 therein, the pistons T, the piston-rod S, the lever V, the valve-boxes K and N, the suction-tube M, and the delivery-tube Q, substantially as herein shown and described, and for the purpose set forth.

LYMAN HALL ZEIGLER.
